Advent, LLP(57) **CLAIM**

The ornamental design for a receptacle for a dispenser, as shown and described.

DESCRIPTION

FIG. 1 is a top plan view of a receptacle for a dispenser. FIG. 2 is a bottom view of the receptacle for a dispenser of FIG. 1.

FIG. 3 is a front elevation view of the receptacle for a dispenser of FIG. 1.

FIG. 4 is a rear elevation view of the receptacle for a dispenser of FIG. 1.

FIG. 5 is a left side elevation view of the receptacle for a dispenser of FIG. 1.

FIG. 6 is a right side elevation view of the receptacle for a dispenser of FIG. 1.

FIG. 7 is an isometric view of the receptacle for a dispenser of FIG. 1; and,

FIG. 8 is another isometric view of the receptacle for a dispenser of FIG. 1.

The broken lines in the drawing depict portions of the receptacle for a dispenser that form no part of the claimed design.
